UNITED STATES PATENT OFFICE.

JAMES T. SIBLEY, OF CLINTON, CANADA, ASSIGNOR, BY MESNE ASSIGNMENTS, TO JOHN M. DRYSDALE, TRUSTEE, OF NEW YORK, N. Y.

PHASE-COMPLETING DEVICE.

SPECIFICATION forming part of Letters Patent No. 552,553, dated January 7, 1896.

Application filed March 28, 1893. Serial No. 467,937. (No model.)

To all whom it may concern:

Be it known that I, JAMES T. SIBLEY, of Clinton, Huron county, Province of Ontario, Dominion of Canada, have invented a new and useful Phase-Completing Device, of which the following is a specification.

Figure 1 of the drawings is a view of the device with the switch lifted out of contact and in position to be forced down by an impulse through the coils of the magnet; Fig. 2, a view of the same with the switch down and contacts closed and the switch locked in place, the dotted lines showing the position of the armature-lever when down and the full lines showing the lever and its pivoted arm when it has passed behind the bracket. Fig. 3 is a view of the same with pin on end of the pivoted arm b^3 in position to force out the arm d^1 and unlock the switch. Fig. 4 is a view of the pivoted hanger on the end of armature-lever and showing position of the spring for operating this hanger to throw its lower end to the right; Fig. 5, a view of the pivoted hanger on center; Fig. 6, a view of pivoted hanger forced to the other side and its spring ready to throw it back.

Viewing Fig. 1, A is a frame, of wood or other suitable material, provided with the binding-posts $a^1 a^2 a^3 a^4$. Upon this frame is suitably mounted the electromagnet B, provided with its armature-lever b^1 and retracting-spring b^2 . The dotted lines on Fig. 3 show the connections with the binding-posts and the line, so that an impulse through the coils of the electromagnet will operate its armature-lever and a break will allow it to be retracted by its spring.

The switch C is pivoted at c^1 . Its normal position is drawn up by the tension of the spring c^2 , as shown in Fig. 1. On the end of this switch is placed the contact c^3 , made of suitable conducting material and arranged to make contact with the plate c^4 when forced down. Attached to the spring is the bracket c^5 , and this bracket is provided on one side with the projection c^6 , and on the other side it is slightly rounded. The bracket c^5 and projection c^6 may be made in two pieces instead of solid, as shown in the figures. On the switch C is also placed a lug, as c^7 , to co-operate with

a checking or locking device hereinafter fully explained.

Suitably pivoted to a part of the frame is the hanger D, provided with the arms $d^1 d^2$. The lower ends of its arms are forced to the right by the spring d^3 and to the left by the downward movement of the armature-lever b^1 . On the end of this armature-lever is pivoted the arm b^3 , which near its lower end is provided with a pin or projection b^4 . When the switch is down the arm d^2 comes in contact with the lug or projection c^7 and holds the switch in position until the arm is forced off of the projection by the passage of the pin b^4 between the bracket c^5 and the arm d^1 , the action of the pivoted arm b^3 is controlled by the spring b^5 secured to the armature-lever at one end with its other end resting on the top of the arm. The action of this spring on the arm b^3 is illustrated in Figs. 4, 5 and 6. When the arm is hanging plumb the spring rests upon the plane top surface of the arm, as shown in Fig. 5. When it is out of plumb, with its lower end to the left of a plumb-line, the spring rests upon the upper left-hand corner of the arm, as shown in Figs. 3 and 4. When it is thrown to the right of a plumb-line the spring rests upon the upper right-hand corner of the arm, as shown in Figs. 1 and 6. Viewing the position of the parts, as shown in Fig. 1, it will be seen that an impulse through the coils of the magnet will force down the armature-lever and the switch until the contacts $c^3 c^4$ are closed, as shown in Fig. 2, which also shows in dotted lines the position of the armature-lever and the arm b^3 . At this point the hanger D has been forced out by its spring d^3 until the arm d^2 has passed above and over the lug c^7 , holding the contacts $c^3 c^4$ closely together. The circuit through the binding-posts $a^3 a^4$ is then closed and remains closed until it is opened by another impulse. In this closed position of the contacts the spring b^5 is resting upon the upper right-hand corner of the arm b^3 , as shown in Fig. 6. When the armature-lever is released and drawn back by its spring b^2 the pin b^4 passes up beyond the top of bracket c^5 , when the spring b^5 throws the arm to the left in the position shown in full lines in Fig. 2, and ready when it descends

- to enter the pin b^4 behind the bracket and between it and the arm d^1 . When another impulse is given and the arm descends the position of the spring b^5 is changed and rests upon the next forward movement of said arm an equal distance to thereby throw out the locking devices and release the phase-completing device.
- 5 the upper left-hand corner of the arm, as shown in Figs. 3 and 4, and in descending actuates the arm d' , disengaging the arm d^2 from the projection c^7 . The switch is then thrown up by the spring c^2 . At the same time 10 the action of the spring b^5 on the arm b^3 throws the pin b^4 to the other side of the bracket, when it takes its position on the seat c^6 ready for another impulse to close the contacts c^3 c^4 . Thus with each impulse the current in that 15 circuit is opened or closed.

The above description represents the action of the device when used upon an open magnet-circuit and its operation in response to impulses; but it will be seen that the same 20 device may be used upon closed circuit by using the retracting-spring of the armature-lever to close the contacts and the impulse through the coils of the magnet to open them.

It will also be seen that the device may be 25 operated by hand and without the use of the magnet B, and that it may also be operated in connection with any other device as well as a switch. For example, by connecting a semaphore or other device to the end of switch-bar C it would be thrown to "safety" by one 30 movement of the switch-bar in a forward or downward direction, and with the next forward movement of the actuating-arm D the locking devices would be released and allow 35 the semaphore to be returned to "danger."

What I claim, and desire to secure by Letters Patent, is—

1. In a phase-completing device provided with an actuating arm therefor, having a forward and a backward movement, and devices 40 for impelling the arm a fixed distance to thereby complete the throw of the phase-completing device, in combination with locking devices actuated by said arm in its forward movement whereby the phase-completing device is locked and retained in position while the arm is withdrawn to complete its backward movement, and releasing devices actuated by

the next forward movement of said arm an equal distance to thereby throw out the locking devices and release the phase-completing device.

2. In a phase-completing device provided with an actuating arm therefor having a forward and backward movement and devices 55 for impelling the arm a fixed distance to complete the throw of the phase-completing device, against the tension of a retractile spring, in combination with locking devices actuated by said arm in its forward movement, whereby 60 the phase-completing device is locked and retained in position, while the arm is withdrawn to complete its backward movement, and releasing devices actuated by the next forward movement of said arm an equal distance to 65 thereby throw out the locking devices, and allow the retractile spring to restore the phase-completing device to starting point.

3. In a circuit changing device the combination with a switch as C provided with the 70 bracket c^5 , of an armature lever provided with a pivoted arm as b^3 , the spring b^5 , arranged in connection therewith, to throw the arm b^3 to one side or the other of the bracket as required.

4. In a phase-completing device provided with an actuating arm therefor having a forward and a backward movement and devices 75 for impelling the arm to complete the throw of the phase-completing device an equal distance with each forward movement, in combination with automatic locking devices to hold and retain the phase-completing device at the end of its course while the impelling devices are withdrawn, and a guiding device, 80 whereby the impelling devices are directed to actuate the phase completing device to the end of its course, and to unlock and release the same at the next forward movement.

Signed at New York, in the county of New 90 York and State of New York, this 22d day of March, A. D. 1893.

JAMES T. SIBLEY.
